(57) **CLAIM**

The ornamental design for a desk as shown and described.

DESCRIPTION

FIG. 1 is a perspective view of the desk;

FIG. 2 is a front elevational view of the desk;

FIG. 3 is a rear elevational view of the desk;

FIG. 4 is a left side elevational view of the desk;

FIG. 5 is a right side elevational view of the desk;

FIG. 6 is a top plan view of the desk;

FIG. 7 is a bottom plan view of the desk;

FIG. 8 is an enlarged view of a disclaimed portion labelled as “8” called out in FIG. 2;

FIG. 9 is an enlarged view of another disclaimed portion labelled as “9” called out in FIG. 2;

FIG. 10 is an enlarged view of a disclaimed portion labelled as “10” called out in FIG. 3; and,

FIG. 11 is an enlarged view of another disclaimed portion labelled as “11” called out in FIG. 3.

The broken lines included in the drawings show portions of the article that form no part of the claimed design.

The broken ellipse lines in FIGS. 2 and 3 demarcating the disclaimed portions are for purposes of annotation and form no part of the claimed design.

1 Claim, 9 Drawing Sheets
